ELECTRIC SHAVER

Walter J. Pasinski, Howell, Mich.

Application July 9, 1942, Serial No. 450,231

7 Claims. (Cl. 30—43)

My invention relates to shaving devices of the type known as electric razors or dry shavers, and it has to do more particularly with the cutting means of such devices and the driving means therefor.

The main object of my invention is to provide an improved electric razor which is simple in construction, inexpensive to manufacture, easy to assemble and disassemble, and adapted to operate with a high degree of shaving efficiency at all times.

Another object is to provide an improved manner of supporting the cutting means of an electric razor.

Still another object is to provide an improved driving mechanism for an electric razor of the rotary or oscillating cutter type.

A further object is to provide an accurately balanced drive mechanism for an electric razor whereby such mechanism is free from chatter, quiet in operation, substantially uniform in operating speed, subject to a minimum of wear, and capable of long use without repair or other maintenance attention.

An additional object is to provide a cutting mechanism for an electric razor which is maintained in proper operable cutting relation in respect to a shear plate without the use of spring or other tensioning means, the cutting operation being of a quiet nature with a minimum of wear so that the cutting means may be used with a high degree of cutting or shearing efficiency over a long period of time without attention.

Another object is to provide a cutting or shearing mechanism for an electric razor which is of the oscillating type and which may be operated at a high, uniform speed with less power than heretofore employed.

A further object is to provide an electric razor embodying the foregoing features wherein there is provided a housing having a main body or handle portion with an extended angular neck portion supporting an oscillatory cutting or shearing member, a driving motor having a rotatable armature shaft located in the handle portion of the housing, and means between the armature shaft and cutting member for converting rotary movement of the former into oscillatory movement of the latter.

Other objects and advantages will become apparent as this description progresses and by reference to the drawing wherein,

Figure 1 is a side elevational view of one form of electric razor embodying my invention;

Fig. 2 is an enlarged vertical sectional view of

the upper portion of the razor shown in Fig. 1, such view being taken through the drive and cutting mechanisms;

Fig. 3 is a horizontal sectional view taken substantially on line 3—3 of Fig. 2;

Fig. 4 is a horizontal sectional view taken substantially on line 4—4 of Fig. 2; and

Fig. 5 is a separated view of the drive mechanism shown in the previous figures and illustrating the different positions assumed by parts of the drive mechanism during operation.

Generally, the electric razor shown in the drawing embodies a housing 10 having a handle portion 10^a with a curved neck portion 11 at its upper end extending upwardly and forwardly therefrom, and a cutting head 12 mounted on the upper end of the neck 11. The operating mechanism, to be described in detail hereinafter, is enclosed and operably mounted within the housing handle 10^a, the neck portion 11 and the cutting head 12.

The cutting head 12 takes the form of a spider member 13 having an annular body portion with a central threaded opening 13^a in which is received the reduced threaded extension 14 of a connecting member 15. The connecting member 15 is threadedly engaged in an opening 11^a in the upper end of the housing neck 11 for detachably connecting the cutting head 12, as a unit, to the housing. The spider 13 carries a shear plate 16 which is of circular form with an annular depending skirt or side wall 17. The side wall 17 of the shear plate 16 is secured to the ends of the radially extending arms 18 of the spider 13 by spot welding or other suitable means. The shear plate 16 has an upper end wall comprising a raised annular shaving surface 19 adjacent its outer edge, and a depressed central portion 20. The annular shaving surface 19 of the shear plate 16 is provided with a plurality of radially extending slots 21 adapted to receive the hair of the user as the shaving surface 19 is passed over and in close contact with the skin of the user's face.

An oscillatory cutter 22 is mounted between the shear plate 16 and the spider 13. Specifically, the cutter 22 comprises a circular, disk-like body portion 22^a having a plurality of annularly spaced, inverted L-shaped cutting teeth 23 around its periphery extending integrally upward and then outward. The cutting teeth 23, in operable position, are adapted to bear against or ride over the inner surface of the annular slotted shaving portion 19 of the shear plate 16 and to oscillate across the slots therein so as to shear

or clip any hairs entering the slots 21. To this end, the spider 13 is provided on its upper surface with an upstanding, annular bearing rim 24 which seats against the body portion 22^a of the cutter 22. The spider 13 is so positioned within the skirt or side wall 17 of the shear plate 16 that the cutter is confined between the spider and shear plate in condition for rotation but with the cutting teeth 23 seated nonyieldingly against the underside of the shaving surface 19. The spider is so positioned that axial play in the cutter is avoided and the cutting teeth engage the shaving surface 19 only with sufficient pressure to insure a close shearing or clipping contact therebetween. By the foregoing construction, the use of springs for urging the cutter member into cutting engagement with the shear plate, as is customary in well known types of electric razors, is eliminated, thereby greatly reducing wear and insuring a long operating life for the razor without repair or replacement of the cutter. Also, with this arrangement, less power is required to oscillate the cutter, and the oscillatory motion of the cutter is carried out quietly with greater uniformity in speed.

The body portion 22^a of the cutter 22 is provided with a central opening 25 which is, preferably, but not necessarily, square. The opening 25 receives a complementally shaped head 26 located on the outer end of an inclined driven shaft 27 which is journaled in an opening 15^a extending downwardly and rearwardly through the bearing 15. It will be noted, in Fig. 2, that the lower end of the bearing member 15 is reduced and extended so as to provide a journaled support for the shaft 27 throughout the length of the latter; and that the lower end of the shaft 27 is supported substantially in vertical alignment with the axis of the handle portion 10^a of the housing. The shaft 27 is oscillated to, in turn, oscillate the cutter 22 by an armature shaft 32 located substantially on the axis of the handle portion 10^a of the housing, and this shaft 32 is adapted to be rotated by an electric motor (not shown) which may take any of the well-known forms employed in electric razors.

Connection between the shafts 27 and 32 is effected by an eccentric drive means. More particularly, this drive means comprises a bifurcate coupling member 29 having a flat body portion 29^a riveted, or otherwise fixedly secured at 28, to the lower end of the shaft 27. The coupling member 29 is also provided with a pair of depending, angularly disposed arms 30 and 31 which extend vertically downward from the body portion 29^a in vertical alignment with the adjacent end of the armature shaft 32 and substantially parallel thereto.

The coupling member 29 is adapted to be driven from the armature shaft 32 by an eccentric drive element mounted upon the upper end of the armature shaft 32. Specifically, a cap plate 33 is mounted upon the upper end of the armature shaft 32, and is secured thereto by a locking screw 34. The cap plate 33 is provided on its upper surface with an upstanding, eccentrically positioned tubular shaft 35 which passes through an opening in, and rotatably supports a ball-shaped drive head 36. The drive head 36 is rotatably secured to the eccentric shaft 35 by a rivet or stud 38 which passes through the tubular shaft 35 and which is provided with heads 38^a and 38^b at its opposite ends for fixing it in place. The upper head 38^b is enlarged and it seats against an upper flattened portion of the ball-

drive head 36 with slight pressure which does not hinder the tendency of the ball head 36 to rotate. The drive ball 36 is so positioned that it is disposed snugly between and is embraced by the arms 30 and 31 of the coupling member 29. Also, the coupling arms 30 and 31 are of sufficient width to remain in drive relation with the ball head 36 as it moves back and forth during rotation of the armature shaft 32, as illustrated in

10 Fig. 5. In this way rotation of the armature shaft 32 drives the coupling member 29 and shaft 27 with an oscillatory motion (Fig. 5).

The electric motor (not shown) is started by rotation of a starting wheel 42 carried at the 15 upper end of the armature shaft 32 projecting through a slot 43 in the side wall of the housing 10, as is customary in prior forms of electric razors.

I believe that the operation and advantages of 20 my invention will be well understood from the foregoing description. When the razor is in operation, the armature shaft 32 rotates at a comparatively high speed and this rotary motion is translated into oscillatory motion by the eccentric connection above described. This oscillatory motion oscillates the shaft 27, in turn oscillating the cutter 22 to move the teeth 23 of the latter back and forth across the slots 21 of the shaving surface 19 to shear any hairs that may be protruding through the slots 21. The cutter is maintained in cutting relation to the shaving surface without springs. This relation is a fixed one and wear is reduced, less power for operation is required, the cutting action is more quiet, the cutting speed is more constant, and the over-all shaving efficiency of the device is greatly improved. The structure as a whole is quite simple. It is rugged and durable so that it may be operated for long periods of time without repair or 30 maintenance attention. Furthermore, the driving mechanism provided by my invention is accurately balanced so that it operates quietly at high speed with a minimum of wear.

I claim:

45 1. An electric razor comprising a housing, a cutting head on one end of said housing comprising a shear plate on the top of said head and a cutter mounted in said head under and in cutting relation to said shear plate, the plane of said cutting head being inclined at an angle to the longitudinal axis of said housing, a rotatable shaft in said housing extending substantially parallel to the longitudinal axis thereof and adapted to be driven by an electric motor, an inclined shaft 50 in the upper portion of said housing connected at its upper end to said cutter and extending downwardly at an angle to the longitudinal axis of said rotatable shaft, and eccentric means operably connecting said rotatable shaft and said inclined shaft and adapted to convert the rotating movement of said rotatable shaft to oscillatory movement of said inclined shaft whereby the cutter is oscillated in said inclined head.

65 2. An electric razor comprising a housing, a cutting head on one end of said housing comprising a stationary shear plate on the top of said head and an oscillating cutter mounted in said head under and in cutting relation to said shear plate, the plane of said cutting head being inclined at an angle to the longitudinal axis of 70 said housing, a rotatable shaft in said housing extending substantially parallel to the longitudinal axis thereof and adapted to be driven by an electric motor, an inclined shaft in the upper portion of said housing connected at its upper

end to said cutter and extending downwardly at an angle to the longitudinal axis of said rotatable shaft, eccentric means carried by the upper end of said rotatable shaft, and a bifurcate member secured to the lower end of said inclined shaft for oscillatory movement therewith and engaged with said eccentric means, whereby rotation of the rotatable shaft causes oscillatory movement of said inclined shaft and, in turn, said cutter.

3. An electric razor comprising a housing, a cutting head on one end of said housing comprising a shear plate on the top of said head and a cutter mounted in said head under and in cutting relation to said shear plate, the plane of said cutting head being inclined at an angle to the longitudinal axis of said housing, a rotatable shaft in said housing extending substantially parallel to the longitudinal axis thereof and adapted to be driven by an electric motor, an inclined shaft in the upper portion of said housing connected at its upper end to said cutter and extending downwardly at an angle to the longitudinal axis of said rotatable shaft, and an eccentrically disposed drive member mounted on the upper end of said rotatable shaft and extending upwardly therefrom, and a bifurcate member secured to the lower end of said inclined shaft and extending downwardly therefrom into engagement with said eccentric member, whereby rotation of the rotatable shaft causes oscillatory movement of said inclined shaft and cutter.

4. An electric razor comprising a housing, a cutting head on one end of said housing comprising a shear plate on the top of said head and a cutter mounted in said head under and in cutting relation to said shear plate, the plane of said cutting head being inclined at an angle to the longitudinal axis of said housing, a rotatable shaft in said housing extending substantially parallel to the longitudinal axis thereof and adapted to be driven by an electric motor, an inclined shaft in the upper portion of said housing connected at its upper end to said cutter and extending downwardly at an angle to the longitudinal axis of said rotatable shaft, a ball-like eccentric member mounted on the upper end of said rotatable shaft and extending upwardly therefrom, and a bifurcate member having a pair of arms rigidly secured to the lower end of said inclined shaft and extending downwardly therefrom to embrace said ball-like eccentric member, whereby rotation of the rotatable shaft causes oscillatory movement of said inclined shaft and said cutter.

5. An electric razor comprising a housing, a cutting head on one end of said housing comprising a shear plate on the top of said head and a cutter mounted in said head under and in cutting relation to said shear plate, the plane of said cutting head being inclined at an angle to the longitudinal axis of said housing, a rotatable shaft in said housing extending substantially parallel to the longitudinal axis thereof and adapted to be driven by an electric motor, an inclined shaft in the upper portion of said housing connected at its upper end to said cutter and extending downwardly at an angle to the longitudinal axis of said rotatable shaft, said inclined

shaft terminating at a point where its longitudinal axis is in substantial alignment with the longitudinal axis of the rotatable shaft, an eccentric member on the upper end of said rotatable shaft, and a bifurcate member secured to the lower end of said inclined shaft and having a pair of arms depending vertically substantially parallel with said rotatable shaft, said arms receiving said eccentric member, whereby rotation of the rotatable shaft is translated into oscillatory movement of said inclined shaft to oscillate said cutter.

6. An electric razor comprising a housing, a cutting head on one end of said housing comprising a shear plate on the top of said head and a cutter mounted in said head under and in cutting relation to said shear plate, the plane of said cutting head being inclined at an angle to the longitudinal axis of said housing, a rotatable shaft in said housing extending substantially parallel to the longitudinal axis thereof and adapted to be driven by an electric motor, an inclined shaft in the upper portion of said housing connected at its upper end to said cutter and extending downwardly at an angle to the longitudinal axis of said rotatable shaft, eccentric means carried by the upper end of said rotatable shaft and including a plate member secured to the upper end of said rotatable shaft for rotatable movement therewith and a ball-shaped member secured off-center relative to the longitudinal axis of said rotatable shaft on the upper surface of said plate member, and a bifurcate member secured to the lower end of said inclined shaft and having arms extending vertically downward therefrom into embracing engagement with said ball-shaped member, whereby rotation of the rotatable shaft causes oscillatory movement of said inclined shaft and cutter.

7. An electric razor comprising a housing, a cutting head on one end of said housing comprising a supporting member secured to the upper end of the housing and having an upwardly directed fixed bearing member on the upper surface thereof, a slotted circular shear plate secured to said supporting member and in spaced relation thereabove, and a circular cutter mounted between said supporting member and said shear plate for free oscillatory movement therebetween without binding, said cutter being confined and maintained against the under surface of said shear plate and in cutting relation thereto by the fixed bearing member of said supporting member, a rotatable shaft in said housing extending substantially parallel to the longitudinal axis thereof and adapted to be driven by an electric motor, an inclined shaft in the upper portion of said housing connected at its upper end to said cutter and extending downwardly at an angle to the longitudinal axis of said rotatable shaft, eccentric means carried by the upper end of said rotatable shaft, and a bifurcate member secured to the lower end of said inclined shaft for oscillatory movement therewith and engaged with said eccentric means, whereby rotation of the rotatable shaft causes oscillatory movement of said inclined shaft and cutter.

WALTER J. PASINSKI.
